UNITED STATES PATENT OFFICE.

JOSIAH S. CUSHING, OF NORWOOD, MASSACHUSETTS.

WHEEL-TIRE.

SPECIFICATION forming part of Letters Patent No. 779,588, dated January 10, 1905.

Application filed September 19, 1904. Serial No. 224,990.

To all whom it may concern:

Be it known that I, JOSIAH S. CUSHING, of Norwood, county of Norfolk, State of Massachusetts, have invented an Improvement in 5 Wheel-Tires, of which the following description, in connection with the accompanying drawings, is a specification, like characters on the drawings representing like parts.

This invention relates to wheel-tires especially designed for automobiles and other vehicles requiring very durable yet moderately resilient tires.

The wheel-tire embodying this invention comprises, essentially, one or more circularly-formed tubular layers, each comprising a plurality of helical springs, which are connected together, and an outer tubular wrapper, preferably elastic, inclosing said layers. Preferably a central yielding core will be contained 20 within the innermost tubular layer. The helical springs may be disposed in parallelism and extend transversely around the tire, or they may extend longitudinally around the tire, and the helical springs will be interlocked together and also additionally connected together by textile material, which is cemented or otherwise connected thereto.

Figure 1 shows a transverse section of a portion of a wheel-tire embodying this invention. Fig. 2 is a plan view of a portion of the wheel-tire. Figs. 3, 4, and 5 are details of one of the tubular layers. Fig. 6 is a longitudinal section of a portion of a tire having a modified form of yielding core. Fig. 7 is 35 a transverse section of a portion of the tire shown in Fig. 6. Fig. 8 is a longitudinal section of a portion of the tire having another modified form of yielding core. Fig. 9 is a transverse section of a portion of the tire 40 shown in Fig. 8. Fig. 10 is a longitudinal section of a portion of the tire having another modified form of yielding core. Fig. 11 is a transverse section of a portion of the tire shown in Fig. 10.

Referring to Figs. 1 and 2, *a* represents the outer tubular wrapper, composed of rubber or other suitable material and constructed in any suitable manner, so far as my invention is concerned.

bb represents several concentrically-disposed

circularly-formed tubular layers which are contained within the outer wrapper *a*. Each tubular layer consists of a plurality of helical springs *b*, (see Figs. 3 to 5,) disposed in parallelism and interlocked together and also additionally connected together by sheets of canvas *c c*, which latter give to the layer a smooth exterior finish. The sheets *c c* of canvas are attached to the helical springs by rubber cement, as shown at *b*². The tubular 55 layers thus constructed are moderately resilient and very durable.

In case the circularly-formed tubular layers are composed of interlocked helical springs made up as flat sheets bent or formed into 65 tubular shape with the edges abutting together extra pieces of canvas *b*⁴ will be wound around them. As many of these layers will be provided as desired, they being concentrically arranged.

Within the innermost tubular layer a yielding core *d* is or may be provided, which will be composed of hemp, as shown in Fig. 1, or it may consist of a circular spring of flat metal, as shown in Figs. 6 and 7, or a helical 75 spring of flat metal, as shown in Figs. 10 and 11, or it may be composed of a helical spring of wire, as shown in Figs. 8 and 9.

Having thus described my invention, what I claim as new, and desire to secure by Letters 80 Patent, is—

1. In a wheel-tire, one or more circularly-formed tubular layers comprising sheets of textile material and a plurality of helical springs connected together which are interposed between said sheets of textile material and attached thereto, and an outer tubular covering inclosing said layers, substantially as described.

2. In a wheel-tire, one or more circularly-formed tubular layers comprising sheets of textile material and a plurality of interlocked helical springs connected together which are interposed between said sheets of textile material and attached thereto, and an outer tubular 95 covering inclosing said layers, substantially as described.

3. In a wheel-tire, one or more circularly-formed tubular layers comprising a plurality of helical springs connected together and 100

sheets of canvas between which said springs are placed and to which they are attached by cement, and an outer tubular covering inclosing said layers, substantially as described.

5. 4. In a wheel-tire, one or more circularly-formed tubular layers comprising sheets of textile material and a plurality of helical springs connected together which are interposed between said sheets of textile material 10 and attached thereto, an outer tubular cover-

ing inclosing said layers, and a yielding core contained within the innermost tubular layer, substantially as described.

In testimony whereof I have signed my name to this specification in the presence of two 15 subscribing witnesses.

JOSIAH S. CUSHING.
